UNITED STATES PATENT OFFICE.

LLOYD BLACKMORE, OF HIGHLAND PARK, MICHIGAN, ASSIGNOR TO GENERAL MOTORS CORPORATION, OF DETROIT, MICHIGAN, A CORPORATION OF DELAWARE.

VEHICLE HEATER.

Application filed April 21, 1924. Serial No. 707,923.

This invention relates to heaters, and is illustrated as embodied in an automobile having a heater embracing part of the exhaust manifold of the engine. An object of the invention is to provide a simple unitary construction, which, preferably, is adapted to be made of sheet metal, and which is readily attached and is neat in appearance.

Having this object in view the heater is provided with a portion embracing a part of the exhaust manifold of the engine and which is secured in place by being drawn toward the manifold and engine in such a manner as to clamp it detachably thereto. In one desirable arrangement the manifold embracing part of the heater is generally channel-shaped in cross section, and engages at its lower edges respectively a horizontal flange on the outer side of the manifold and a horizontal surface on the engine adjacent the inner side of the manifold, and attaching devices such as bolts tapped into the manifold are provided for drawing this portion of the heater downwardly to clamp it detachably against the manifold and engine.

Another feature of the invention relates to the provision of a heater adapted for use with an engine having an intake manifold, and an exhaust manifold which jackets a part of the intake manifold, and in which the heater is arranged to embrace a substantial part of the exhaust manifold without enclosing any part of the intake manifold. As the exhaust jacket is usually made integral with the intake manifold in constructions of this character, this arrangement provides a heater which in no way interferes with the removal of the intake manifold at any time.

The invention also contemplates efficiently insulating the heater from the interior of the vehicle when it is not being used, by closing the shutter or other control device leading into the vehicle body, and concurrently diverting the heated air away from the shutter.

The above and other objects and features of the invention, including various desirable particular constructions, will be apparent from the following description of an illustrative embodiment shown in the accompanying drawings, in which:

Figure 1 is a diagrammatic side elevation of the internal combustion engine of an

automobile with adjacent parts of the body shown in vertical section;

Figure 2 is a section on the line 2-2 of Figure 1 showing the relation of the vehicle heater to the exhaust jacketed part of the intake manifold; and

Figure 3 is a section on the line 3-3 of Figure 1 showing the manner of clamping the heater against the exhaust manifold.

In the arrangement selected for illustration the invention is embodied in an automobile having an internal combustion engine 10 provided with an intake manifold 12 having a vertical portion 14 to which the carburetor connections are secured. The engine also has a generally horizontal exhaust manifold 16 having at its center an open part 18 arranged to register with a jacket 20 surrounding part of the intake manifold in such a manner as to provide what is sometimes called a "hot spot". The exhaust manifold 16 communicates in the usual manner with a conduit 22 leading to the muffler. In Figure 1 is shown part of the floor board 24 and the lower part of the dash 26.

The present invention relates to a vehicle heater shown as having a funnel shaped rear portion 28 leading to a driver controlled closure such as a shutter 30 in the floor board 24. An important minor feature of novelty comprises the use of means for diverting the heater air from the shutter when it is closed, to prevent undesirable heating of the floor board, as by an auxiliary shutter 29 connected to shutter 30 by links 31 in such a manner that it is in full-line position (Figure 1) when shutter 30 is open, and is in dotted line position when shutter 30 is closed. It will be evident that when the auxiliary shutter 29 is in dotted line position, the heated air will be diverted through an opening in the top of the part 28 of the heater.

Forwardly of the funnel shaped portion 28 the heater is in the form of a channel shaper portion 32 open at its front end to receive part of the air drawn rearwardly through the radiator by the fan. This portion of the heater engages at its outer lower edge a supporting part such as a grooved horizontal flange 34 on the outer face of the exhaust manifold 16 at opposite sides of jacket 20, and is arranged at its center to engage the top face of the part 18 of the exhaust manifold as shown in Figure 2 so that no part of the intake manifold or its jacket

- 20 is enclosed in the heater, and consequently the intake manifold can be removed by taking out the attaching bolts 36 without disturbing the heater. The inner lower edge of the portion 32 of the heater rests on a horizontal surface adjacent and parallel to the inner face of the exhaust manifold 16 and which is formed as a ledge along the edge of the cylinder head 38 of 10 the engine 10. The portion 32 of the heater is preferably also provided with a partial bottom closure or flange 40 bridging the space between the cylinder head 38 and the inner face of the exhaust manifold 16, 18. 15 The heater is clamped detachably in place by draw bolts 42 tapped into the upper face of the exhaust manifold and which carry wing nuts 44 for drawing the heater downwardly to clamp it firmly against the flange 34 and the upper surface of the portion 18 of the manifold and against the horizontal surface or ledge of the cylinder head 38.

According to an important feature of the invention, the upper face of the exhaust manifold is provided with a plurality of heat radiating fins 46 shown as being integral with the manifold and extending longitudinally thereof. Thus the heat-radiating fins are inclosed by the heater.

20 It will be seen that the construction described is suitable for manufacture in large quantities at a low cost, of sheet metal, and that it is in one single piece without horizontal or other joints. Moreover, it can 25 very quickly and easily be attached and detached by means of the draw bolts 42 and the wing nuts 44.

While one illustrative embodiment of the invention has been described in detail it is 30 not my intention to limit its scope to that particular embodiment or otherwise than by the terms of the appended claims.

I claim:

1. A heater for vehicles comprising an 35 internal combustion engine having an exhaust manifold provided with an opening, an intake manifold having a jacket engaging the opening, a heater casing enclosing the

upper part of the exhaust manifold and engaging the wall of the exhaust manifold 50 within the line of junction of the jacket and exhaust manifold to permit the removal of the intake manifold without removing the heater casing.

2. A heater for vehicles comprising an internal combustion engine having an exhaust manifold, the exhaust manifold having an opening, an intake manifold provided with a jacket engaging the opening of the exhaust manifold, a U-shaped heater casing enclosing the upper part of the exhaust manifold and engaging by its outer wall the horizontal part of the exhaust manifold, the engagement of the casing at that portion of the manifold having the opening being within 60 the line of junction of the intake jacket with the exhaust manifold to permit the removal of the intake manifold without removing the heater casing.

3. A heater for vehicles, comprising a U-shaped heater casing, an internal combustion engine having an exhaust manifold provided with an integral supporting flange on its outer face extending horizontally of the manifold, said engine also having a horizontal supporting portion adjacent the inner face of the manifold, the horizontal supporting portion of the engine and integral horizontal flange of the manifold forming seats upon which said casing rests, and a hold-down bolt extending vertically between the manifold and casing, and being adapted to downwardly clamp said casing on its seats.

4. A heater for vehicles, comprising a U-shaped heater casing, an internal combustion engine having an exhaust manifold, provided with an integral supporting flange on a side wall and extending horizontally thereof, and on which a lower marginal edge of the casing rests, and vertically extending hold-down connections adapted to draw said casing downwardly and hold the same upon said horizontal supporting flange.

In testimony whereof I affix my signature.

LLOYD BLACKMORE.
